UNITED STATES PATENT OFFICE.

ERNEST L. EWBANK, OF HENDERSONVILLE, NORTH CAROLINA, ASSIGNOR
OF TWO-THIRDS TO WILLIAM B. HALLET, OF SPARTANBURG, AND J. L.
TRIBBLE, OF ANDERSON, SOUTH CAROLINA.

NON-REFILLABLE BOTTLE.

SPECIFICATION forming part of Letters Patent No. 622,612, dated April 4, 1899.

Application filed August 29, 1898. Serial No. 689,768. (No model.)

To all whom it may concern:

Be it known that I, ERNEST L. EWBANK, a citizen of the United States, residing at Hendersonville, in the county of Henderson and State of North Carolina, have invented certain new and useful Improvements in Non-Refillable Bottles; and I do hereby declare the following to be a full, clear, and exact description of the invention, such as will enable others skilled in the art to which it appertains to make and use the same.

My invention relates to improvements in bottles and jugs and means for stoppering the same in such a manner that the stopper cannot be removed from the said bottle or jug after being once fully inserted without so changing the appearance of the vessel as to show that the said stopper has been removed.

The object of my invention is to prevent fraud in refilling the vessels with spurious liquids and selling the bottles so refilled as genuine, to the injury of the original manufacturer of the genuine contents.

My invention will be understood by reference to the accompanying drawing, wherein is represented a central longitudinal section through a bottle-neck fitted with a stopper constructed according to my invention.

The neck of the bottle or jug is preferably made thick, as seen at A, and at a point distant from the mouth thereof about equal to half the length of the stopper is provided with a deep surrounding groove a^0 , that portion of the neck of the bottle immediately above such groove being made externally thicker, as shown at A^0 .

That portion of the interior of the neck of the bottle into which the stopper is to fit is made smooth and of approximately a uniform diameter, although it may be preferable to have the same enlarged inwardly.

Within the neck of the bottle, in the thickened portion A^0 thereof, is formed an annular groove a . This groove is located a short distance from and above the exterior annular groove a^0 , so that but a thin portion a' , extending around the neck of the bottle, separates these two grooves. The upper side of this annular groove a is made flat and lies in a plane at approximately right angles to the

interior surface of the stopper-seat, so as to hold the stopper-lock, hereinafter described. The stopper used, as shown at B^0 , is provided with a central axial opening and is fitted with a central tube b^0 , which projects slightly from the upper end of the stopper and is exteriorly screw-threaded to receive a cap b^7 , as shown.

The stopper is locked in the neck of the bottle by a locking-cap C. This cap has a pair of depending legs $c' c'$, provided with oppositely-disposed catch-lugs $c^2 c^2$ upon their lower or free ends adapted to engage in the annular groove a in the bottle-neck above referred to. The locking-cap C is provided with a central screw-threaded opening which fits the screw-threaded end of the tube b^0 and is applied to the stopper by being screwed down over the upper end of the said tube. The screw-threaded end of the said tube is long enough to receive the cap b^7 after the said tube passes through the locking-cap C. The tube b^0 is fitted with a plurality of valves b^8 , which open from opposite sides. The object of these valves is to cause the bottle to become closed immediately upon being stood erect upon its bottom and to prevent the bottle being refilled, the cross-pins b^9 serving as stops to limit the swing of the valves in opening.

The stopper is forced into the neck of the bottle with the cap C thereon, and as forced inward the soft material of the stopper will allow the said legs $c' c'$ to spring inwardly somewhat; but as soon as the catch-lugs $c^2 c^2$ on said legs reach the interior groove a they spring outwardly and engage in said groove, locking the stopper securely in the neck of the bottle. The stopper can then only be removed by breaking the neck of the bottle, which is done by means of some suitable instrument, such as the back of a knife, the line of strike being indicated by the arrow marked 1.

The stopper shown is particularly adapted for use with bottles containing expensive liquids, such as perfumery, where it is desirable to use but a small portion of the liquid at one time and to avoid evaporation, but is also adapted for use with condiments—such as sauces, catsup, &c.—which are discharged

from the bottle in small quantities and at varying intervals of time, and the valves in the central tube prevent the adulteration of the original contents of the bottle.

5 After the bottle-neck is broken it is rendered useless as an original package for re-filling; but the metallic locking-cap C and the stopper may, if desired, be saved and used upon other bottles.

10 Having thus described my invention, what I claim, and desire to secure by Letters Patent of the United States, is—

15 1. In a bottle-stopper, the combination with a yielding plug having a central axial opening therethrough; a tube fitting said opening and projecting beyond the upper end of said plug, the projecting end of said tube being externally screw-threaded; a plurality of outwardly-opening valves in said tube; of a locking device consisting of a disk having a screw-threaded opening, screwed down over the screw-threaded portion of said tube upon said plug; and expanding locking-legs on said disk

adapted to engage outwardly into a groove in the bottle-neck, substantially as described. 25

2. In a bottle-stopper, the combination with a yielding plug having a central axial opening therethrough; a tube fitting said opening and projecting beyond the upper end of said plug, the projecting end of said tube being 30 externally screw-threaded; a plurality of outwardly-opening valves in said tube; and means for limiting the throw of said valves; of a locking device consisting of a disk having a central screw-threaded opening, screwed down over the said screw-threaded portion of said tube upon said plug; and spring-catches on said disk adapted to expand into grooves in the bottle-neck, substantially as described. 35

In testimony whereof I affix my signature 40 in presence of two witnesses.

ERNEST L. EW BANK.
